(57) **ABSTRACT**

A new and distinct cultivar of *Xerochrysum* plant named 'Bonier 1639', characterized by its upright, mounding and uniform plant habit; vigorous growth habit; freely flowering habit; relatively large inflorescences with bright yellow-colored involucral bracts; and strong peduncles that hold the inflorescences above the foliar plane.

1 Drawing Sheet

1

Botanical designation: *Xerochrysum bracteatum*.
Cultivar denomination: 'BONXER 1639'.

BACKGROUND OF THE INVENTION

The present invention relates to a new and distinct cultivar of *Xerochrysum* plant, botanically known as *Xerochrysum bracteatum*, and hereinafter referred to by the name 'Bonier 1639'.

The new *Xerochrysum* plant is a product of a planned breeding program conducted by the Inventors in Yellow Rock, New South Wales, Australia. The objective of the breeding program is to create and develop new upright *Xerochrysum* cultivars with upright and uniformly mounded plant habit, freely flowering habit and attractive inflorescences and inflorescence buds.

The new *Xerochrysum* plant originated from a cross-pollination by the Inventors on Sep. 16, 2015 of a proprietary selection of *Xerochrysum bracteatum* identified as code number 14-8, not patented, as the female, or seed, parent with a proprietary selection of *Xerochrysum bracteatum* identified as code number 14-76, not patented, as the male, or pollen, parent. The new *Xerochrysum* plant was discovered and selected by the Inventors as a single flowering plant within the progeny of the stated cross-pollination in a controlled greenhouse environment in Yellow Rock, New South Wales, Australia on Aug. 1, 2016.

Asexual reproduction of the new *Xerochrysum* plant by terminal cuttings in a controlled greenhouse environment in Yellow Rock, New South Wales, Australia since August,

2

2016, has shown that the unique features of this new *Xerochrysum* plant are stable and reproduced true to type in successive generations.

5 SUMMARY OF THE INVENTION

Plants of the new *Xerochrysum* have not been observed under all possible combinations of environmental and cultural conditions. The phenotype may vary somewhat with 10 variations in environment such as temperature and light intensity, without, however, any variance in genotype.

The following traits have been repeatedly observed and are determined to be the unique characteristics of 'Bonier 1639'. These characteristics in combination distinguish 'Bonier 1639' as a new and distinct *Xerochrysum* plant:

1. Upright, mounding and uniform plant habit.
2. Vigorous growth habit.
3. Freely flowering habit.
4. Relatively large inflorescences with bright yellow-colored involucral bracts.
5. Strong peduncles that hold the inflorescences above the foliar plane.

In side-by-side comparisons, plants of the new *Xerochrysum* differ primarily from plants of the female parent selection in the following characteristics:

1. Leaf margins of plants of the new *Xerochrysum* are more undulate than leaf margins of plants of the female parent selection.
2. Inflorescence buds of plants of the new *Xerochrysum* are more orange in color and not as yellow as inflorescence buds of plants of the female parent selection.

In side-by-side comparisons, plants of the new *Xerochrysum* differ primarily from plants of the male parent selection in involucral bract color as plants of the new *Xerochrysum* have yellow-colored involucral bracts whereas plants of the male parent selection have red-colored involucral bracts.

Plants of the new *Xerochrysum* can be compared to plants of the *Bracteantha bracteata* 'Bonxero 148', disclosed in U.S. Plant Pat. No. 30,398. In side-by-side comparisons, plants of the new *Xerochrysum* differ primarily from plants of 'Bonxero 148' in the following characteristics:

1. Plants of the new *Xerochrysum* are broader than plants of 'Bonxero 148'.
10
2. Plants of the new *Xerochrysum* are more freely branching than plants of 'Bonxero 148'.
15
3. Leaf margins of plants of the new *Xerochrysum* are more undulate than leaf margins of plants of 'Bonxero 148'.
20
4. Plants of the new *Xerochrysum* are more freely flowering than plants of 'Bonxero 148'.
25
5. Inflorescences of plants of the new *Xerochrysum* have darker yellow-colored involucral bracts than inflorescences of plants of 'Bonxero 148'.
30
6. Inflorescences of plants of the new *Xerochrysum* have darker orange-colored disc florets than inflorescences of plants of 'Bonxero 148'.
35
7. Plants of the new *Xerochrysum* have shorter peduncles than plants of 'Bonxero 148'.
40

BRIEF DESCRIPTION OF THE PHOTOGRAPHS

The accompanying photographs illustrate the overall appearance of the new *Xerochrysum* plant. These photographs show the colors as true as it is reasonably possible to obtain in colored reproductions of this type. Colors in the photographs may differ slightly from the color values cited in the detailed botanical description which accurately describe the colors of the new *Xerochrysum* plant.
35

The photograph at the top of the sheet (FIG. 1) is a side perspective view of a typical flowering plant of 'Bonier 1639' grown in a container.
40

The photograph at the bottom of the sheet (FIG. 2) is a close-up view of a typical inflorescence of 'Bonier 1639'. In this photograph, the receptacle is noticeable in between the bracts.
45

DETAILED BOTANICAL DESCRIPTION

The aforementioned photographs and following observations and measurements describe plants grown during the early summer in 24-cm containers in an outdoor nursery in Higashiomii, Shiga, Japan and under conditions and practices which approximate those generally used in commercial *Xerochrysum* production. During the production of the plants, day temperatures averaged 23° C. and night averaged 13° C. Measurements and numerical values represent averages for typical flowering plants. Plants were four months old when the photographs were taken and five months old when the detailed description was taken. In the following description, color references are made to The Royal Horticultural Society Colour Chart, 2001 Edition, except where general terms of ordinary dictionary significance are used.

Botanical classification: *Xerochrysum bracteatum* 'Bonier 1639'.

Parentage:

Female, or seed, parent.—Proprietary selection of *Xerochrysum bracteatum* identified as code number 14-8, not patented.

Male, or pollen, parent.—Proprietary selection of *Xerochrysum bracteatum* identified as code number 14-76, not patented.

Propagation:

Type.—Terminal vegetative cuttings.

Time to initiate roots, summer.—About seven days at temperatures about 18° C. to 21° C.

Time to initiate roots, winter.—About ten days at temperatures about 18° C. to 21° C.

Time to produce a rooted cutting, summer.—About three weeks at temperatures about 18° C. to 21° C.

Time to produce a rooted cutting, winter.—About four weeks at temperatures about 18° C. to 21° C.

Root description.—Fibrous; typically white in color, actual color of the roots is dependent on substrate composition, water quality, fertilizer type and formulation, substrate temperature and physiological age of roots.

Rooting habit.—Freely branching; medium density.

Plant description:

Plant form and growth habit.—Upright, mounding and uniform plant habit with inflorescences held above the foliage on strong peduncles; vigorous growth habit.

Plant height.—About 45 cm.

Plant diameter or spread.—About 63 cm.

Lateral branches.—Quantity per plant: Freely branching habit with about eleven lateral branches per plant. Length: About 15.6 cm. Diameter: About 4.7 mm. Internode length: About 2.5 cm. Aspect: Upright to somewhat outwardly. Strength: Strong. Texture: Rough, sparsely pubescent. Color: Close to 138A.

Leaf description.—Arrangement: Alternate, simple; sessile. Length: About 9 cm. Width: About 2.5 cm. Shape: Linear. Apex: Acuminate. Base: Attenuate. Margin: Entire; slightly undulate. Texture, upper and lower surfaces: Rough, glabrous. Venation pattern: Pinnate; reticulate. Color: Developing leaves, upper surface: Close to 137A. Developing leaves, lower surface: Close to 137C. Fully expanded leaves, upper surface: Close to NN137A; venation, close to 144B. Fully expanded leaves, lower surface: Close to 138A; venation, close to 145A.

Inflorescence description:

Appearance.—Terminal double-type inflorescence form with narrowly deltoid to lanceolate involucral bracts; involucral bracts and disc florets developing acropetally on a capitulum; inflorescences positioned above the foliar plane on strong peduncles; inflorescences face mostly upright.

Flowering habit.—Freely flowering habit; about 51 inflorescences develop per plant during the flowering season.

Fragrance.—None detected.

Time to flower.—In Japan, plants begin to flower about 21 weeks after planting and in the garden, plants flower continuously from the spring through the autumn.

Post-production longevity.—Inflorescences maintain good substance for about seven to ten days on the plant; inflorescences persistent.

Inflorescence buds.—Height: About 2.1 cm. Diameter: About 1.3 cm. Shape: Ovoid with acute apex. Color: Distally, close to N34A and proximally, close to 17B. ⁵
Inflorescence size.—Diameter: About 7.2 cm. Depth (height): About 2.4 cm. Disc diameter: About 3 cm. Disc height: About 1.7 cm.

Receptacles.—Diameter: About 2.6 cm. Height: About 6 mm. Color: Close to 149D.

Involutal bracts.—Quantity per inflorescence and arrangement: About 248 arranged in numerous whorls; bracts imbricate. Length: About 2.3 cm. ¹⁰ Width: About 6 mm. Shape: Narrowly deltoid to lanceolate. Apex: Acuminate. Base: Truncate. Margin: Entire. Texture, upper and lower surfaces: Smooth, glabrous; papery. Orientation: Initially upright becoming horizontal with development. Color: When opening and fully opened, upper surface: Close to 13A and 1B. When opening and fully opened, lower surface: Close to 3A and 1B. ¹⁵

Disc florets.—Quantity per inflorescence and arrangement: Numerous disc florets are spirally arranged in the center of the receptacle. Length: About 7.3 mm. Diameter, distally: About 0.6 mm. Diameter, proximally: About 0.5 mm. Shape: Tubular; apex dentate, five-pointed. Texture, inner and outer surfaces: Smooth, glabrous. Color: When developing, inner and outer surfaces: Close to 24A. Fully developed, ²⁰ ²⁵

inner and outer surfaces: Close to 149D and towards the apex, close to N25A to N25B.

Peduncles.—Length: About 8 cm. Diameter: About 3.3 mm. Strength: Strong. Aspect: Upright to somewhat outwardly. Texture: Rough, glabrous. Color: Close to 144A.

Reproductive organs.—Androecium: Quantity per disc floret: About five. Filament length: About 4.6 mm. Filament color: Close to 157D. Anther size: About 1.8 mm by 0.8 mm. Anther shape: Lanceolate. Anther color: Close to 23A. Pollen amount: None observed. Gynoecium: Quantity per disc floret: One. Pistil length: About 9 mm. Stigma shape: Bi-parted. Stigma color: Close to 25B. Style color: Close to 157D. Ovary color: Close to 155A.

Seeds and fruits.—To date, seed and fruit production has not been observed on plants of the new *Xerochrysum*.

Pathogen & pest resistance: To date, plants of the new *Xerochrysum* have not been shown to be resistant to pathogens and pests common to *Xerochrysum* plants.

Temperature tolerance: Plants of the new *Xerochrysum* have been observed to tolerate temperatures ranging from about 0° C. to about 35° C.

It is claimed:

1. A new and distinct *Xerochrysum* plant named 'Bonier 1639' as illustrated and described.
